UNITED STATES PATENT OFFICE.

LUZENA HOSEA, OF INDIANAPOLIS, INDIANA.

ATHLETIC BELT.

1,312,400.

Specification of Letters Patent.

Patented Aug. 5, 1919.

Application filed September 26, 1917. Serial No. 193,818.

To all whom it may concern:

Be it known that I, LUZENA HOSEA, a citizen of the United States, residing at Indianapolis, in the county of Marion and State 5 of Indiana, have invented certain new and useful Improvements in Athletic Belts, of which the following is a specification.

My invention relates to an improvement in athletic belts for female apparel and the 10 object is to provide a light, tight-fitting belt adapted to be worn and fastened around the loins fitting down in front under the abdomen whereby to afford support for the latter from beneath, and also provide a 15 means for the support of the hose.

My invention consists in a belt cut in the form of a partial circle at the upper edge and the lower, in the main, is approximately 20 parallel, tapering to a point approximately in the form of a right angle or a little less so that the belt fits across the back, with the upper edge at the waist line, and snugly 25 around the small of the back and tightly around the hips and in front the upper edge extends somewhat below the waist line and the lower edge follows the trunk approximately at a line coincident with the line of 30 juncture of the legs and body with an opening at the center which embraces the abdomen from beneath and on each side of the 35 center, with supporters attached at this angle and also a slight distance therefrom for the support of the hose, the tension beneath the abdomen being produced by the fastening at the meeting ends of the belt and the tension of the supporters at the lower edge which are disposed in such a direction as to create the supporting effect mentioned.

In the accompanying drawings:

40 Figure 1 is a view in perspective of the belt from the front.

Fig. 2 is a view of the belt stretched out flat.

Fig. 3 is a front view showing it applied.

45 Fig. 4 is a rear view showing the belt applied.

The numeral 1, represents the belt which may be made of any suitable wash fabric preferably in two or more thicknesses to 50 give the required strength and rigidity with the edges turned in and stitched together. The ends are provided with any suitable fastening means such as hooks and eyes 2 and 3.

55 The ends 4, of the belt are preferably slightly narrower than the main or interme-

diate portion and at the lower edge 5, diverge at which point the belt is somewhat wider than the remaining portion and an angle 6, is formed at this point perhaps a little less than a right angle whence the lower edge of the belt gradually returns to the width of the main portion, thus giving in effect a triangular formation 7, at this point.

Supporters 8, are attached at this angle 65 and extend approximately in line with the diverging edge 5.

Another supporter 9, is attached to the lower edge approximately at right angles thereto so that the two supporters on either 70 end of the belt preferably converge toward the point of fastening to the hose and the two supporters on the two ends consequently diverge from each other as shown.

There is an object in this particular arrangement and disposition of the supporters as there is in the form and shape of the entire belt, for when applied the back portion of the belt starting from the waist line, lies flat upon and fits snugly over the back and then around the hips holding them firmly and thence in front along a line somewhat below the belt line at a point at about where the abdomen commences to curve inwardly so that the fastened ends are under the inwardly curved central portion of the abdomen after which the end parts diverge as shown along the lines 5, where the tension of the supporters 8 is applied as is also the inner lower edge of the triangular portion 90 7, formed by the angle 6, which, with the other supporter 9, holds the belt down while the wearer is standing or walking, tight under the lower portion of the abdomen thus affording a firm, smooth and tight support from beneath the abdomen.

This belt may be worn with or without a corset and its primary function is as its name implies, to afford a support for the lower abdomen from beneath and as such 100 its construction is of a character to afford perfect freedom in movement of the body and at the same time to hold and support the abdomen and the hose and the construction is such that it yields readily to the motions of the body while in a sitting as well as standing posture and tending to slip up and out of the way as the wearer sits, loosening the tension of the supporters and as the wearer again stands resuming its normal 110 position of tension at and around the parts described, with whatever strain and tension

there may be, distributed throughout the entire surface of the body embraced by the belt.

It is my intention to make these in several sizes, perhaps as many as five or six.

Also, my invention contemplates the possibility of putting in a rubber strip at the back to provide for slight variations in the size of the figure to be fitted.

10 I claim:

An athletic belt made of flexible material of suitable width, the upper and lower edges of which are substantially parallel throughout the main and central portion of the belt,

the extreme ends each having an obtuse formation, the upper sides of the obtuse angles provided with fastening means and the lower sides of the angles diverging and leaving an open space, and hose-supporters fastened in pairs to the lower edge of the belt, so that the two supporters of each pair converge toward their lower ends, one supporter of each pair being approximately in line with the lower side of the obtuse formation at the end of the belt.

25 In testimony whereof I affix my signature.

LUZENA HOSEA.
